CHECK PROTECTOR

Lloyd H. Fenstermaker, Aurora, Ill.

Application June 16, 1947, Serial No. 754,880

6 Claims. (Cl. 101—95)

1

The invention relates to a check protector or check writer and has for its principal object the provision of an improved machine having greater stability, increased operating efficiency, and wider flexibility to the extent that it is able to handle all forms of checks and attached vouchers.

The invention accomplishes the foregoing and other objects by the provision of a machine having a body including an elongated generally rectangular base, the length of the sides of which is considerably greater than the width of the ends, which construction provides a more stable check protector in that the increased length of the machine virtually precludes skewing or upset of the machine during operation. The preferred form of construction herein set forth further achieves the object of wider flexibility, in the handling of checks of the type in which a voucher is attached to the longitudinal edge thereof, by the provision of a check-receiving throat of increased depth, the construction being such that the machine is able to handle other types of checks or check-voucher sheets. Still further, the increased length of the machine provides for a more efficient arrangement of the operating mechanism, to the end that each set of operating linkage has an increased mechanical advantage.

In the machines of the type heretofore known, the operating linkage was arranged in a relatively crowded manner, with the result that such machines could operate at near efficiency only by increased travel of certain of the operating parts. One example of this prior construction consisted in the disposition and mode of operation of the operating crank, wherein the crank assumed an initial position inclined rearwardly and away from the operator at the front of the machine. It was further necessary that the crank swing through a rather considerable arc to effect actuation of the printing and shredding mechanism. Such arrangement of the operating lever required an initial movement of the lever upwardly and then forwardly and downwardly, with the result that initial movement of the lever tended to raise the rear end of the machine. Furthermore, machines of prior construction were relatively short and were quite unstable, which condition coupled with the requirement of a considerable horizontal component of operating force necessarily applied to the operating handle is conducive to the machines skewing about and otherwise present problems that prevented quick and efficient check writing.

The foregoing disadvantages are eliminated in a machine constructed according to the principles of the present invention, the structural and oper-

2

ational features of which will appear in the following detailed description of a preferred embodiment of the invention as shown in the accompanying sheets of drawings in which:

Fig. 1 is a three-quarter perspective view showing the external appearance of the machine;

Fig. 2 is a longitudinal sectional view through the machine showing the operating parts in their initial positions;

Fig. 3 is a view similar to Fig. 2 but showing the operating parts in the positions they assume to accomplish the printing and shredding operation;

Fig. 4 is a plan view of the machine with the outer casing removed; and

Fig. 5 is a diagrammatic illustration of one form of check-voucher sheet that the machine disclosed herein is particularly adapted to handle.

Figs. 6 and 7 are fragmentary views taken similarly to Figs. 2 and 3 of a machine employing a modified form of clearing bail operating mechanism and a modified arrangement of return spring for the operating lever and clearing mechanism.

The machine chosen for the purpose of illustration here comprises a body having a base 10, of elongated generally rectangular construction, and a head 11. The length of each of the sides of the base 10 is considerably greater than the width of an end of the base (Fig. 4), thus providing for greater stability of the machine. Each end of the base is provided with a pair of rubber pads or feet 12 for facilitating the use of the machine on smooth surfaces. The head 11 of the machine is substantially enclosed in a case 13, which may be formed of plastic or any other suitable material. The case 13 includes at its front end a cover or arcuate shield portion 14 provided with a plurality of vertical slots 15, the purpose of which will presently appear. The head 11 is substantially coextensive in length and width with the base 10 and is connected at its rear end to the base as at 16. In a preferred form of construction side plates 17 are common to the base and head and each side plate is cut out as at 18 to provide an elongated tapering slot. The cover or shield 14 terminates a short distance above the front portion of the slot 18 and meets a transverse relatively narrow cover portion 19. The narrow portion extends transversely across the front of the head 11 and is spaced above the top of the base 10 to correspond with the spacing of the front end of each slot 18 above the base. The base is provided with a substantially flat upper surface 20. The head 11 may thus be said to be

spaced vertically above the base 10 throughout

substantially its entire length and the space between the base and head provides an elongated throat 21, open at its front and opposite sides and closed at its rear by the portions 16 and the back of the casing 13. The purpose of the throat will be set forth below.

The head 11 carries adjacent its forward end a transverse shaft 22 on which is mounted a plurality of type-carrying members 23. Each member includes an arcuate portion 24 on the outer surface of which is provided type 25 preferably representing digits zero to nine. The type-carrying members are individually settable by means of finger-operated levers 26 that project forwardly respectively through the vertical slots 15 in the front cover or shield 14. The shaft 22 carries rigidly thereon a plurality of depending supports 27 spaced axially thereof and each having at its bottom a transverse type bar 28. These bars extend lengthwise of the shaft 22 and between their opposed ends there are spaces to accommodate respective groups of the type-carrying members 23. These bars carry the usual printing characters for printing appropriate legends such as "dollars" and "cents." Rearward extensions of the type bars carry a transverse shredder member 29 which is an element of mechanism for shredding or perforating the check over the name of the payee.

The base 10 carries at a point substantially midway between its front and rear ends a transverse shaft 30 on which is mounted a pair of longitudinally extending rocker arms 31-31^a. These arms, as will appear subsequently, are connected together for movement as one and carry at their forward ends a printing platen 32 and a shredding or perforating bar 33. When the bars 32 and 33 are moved by the rocker arms 31 from the position shown in Fig. 2 to the position shown in Fig. 3, the platen 32 cooperates with the type 25 and type bars 28 to print the amount of the check and the shredder bar 33 cooperates with the transverse member 29 to perforate or shred the check over the name of the payee, the check having been inserted in the throat 21 between the cooperating parts just described.

Each type-carrying member 23 is provided with a serrated portion 34 of which the notches are engageable by respective spring-pressed detent members 35 to maintain the type characters 25 exactly on the printing line for cooperation with the platen bar 32. Detent members 35 are flat stampings of bell-crank shape and are urged into the notches of the serrations 34 by respective springs 32^a. A transverse bar 32^b carried by the side plates 17 supports a plate 32^c from which detent-carrying brackets 32^d depend. These brackets and the detents 35 pivotally carried thereby are individually adjustable, when screws 32^e are loosened, to properly align the positions or repose of the type 25 within the printing line.

The rocker arms 31 and 31^a extend rearwardly and each has its rear end disposed rearwardly of the throat 21, or at a point substantially between the side plate portions 16 that connect the base and the head 11. At this point the rear ends of the rocker arms are connected by pivot pins 36 to respective lower links 37 and 37^a of toggle mechanism also comprising upper links 38 and 38^a. The upper links 38 and 38^a are pivoted on opposite end portions of a cross rod 39 connected between rear upper portions of the side plates 17. Said upper and lower links are pivotally connected by a transverse pin 40 which also

connects the toggle mechanism to forwardly extending operating links 41 and 41^a therefor having their forward ends pivotally connected to pins 42 respectively carried by rockable plates 43 and 43^a keyed to opposite end portions of a transverse rock shaft 44 having its opposite ends journaled in the side plates 17. This rock shaft 44 is manually rocked and is the operating shaft of the machine. Said rock shaft is disposed substantially midway between the printing and shredding mechanism and the rear end of the body.

The rockable plate 43, Figs. 2 and 3, is in the form of a bell crank having first and second crank arms 45 and 46. This bell crank plate is part of clearing mechanism for the type segments 23, described in detail hereinafter.

Inking means for the type characters which happen to be set in the printing line is suspended by arms 48 and 48^a pivotally supported by axially aligned pins 47 (one being shown in Figs. 2 and 3) respectively anchored in the side plates 17 above the segment-carrying rod 22. This inking means includes an ink tray 49 and inking rollers 50 constituting a unit detachably mounted on the lower ends of the arms 48. Arms 48 and 48^a have extensions 51 which are respectively pivotally connected by pins 52 to rearwardly and slightly downwardly extending links 53 and 53^a.

The rear end of the link 53 is pivoted at 54 to a short arm 55 which is pivotally anchored to the proximate side plate 17 by a pin 56. The pivot pin 54 serves further as means by which the links 53 and 55 are connected to an actuating link 57, the other end of which is carried by the pin 40 that connects the link 41 to the toggle mechanism 37-38. Corresponding parts, designated by the same reference characters plus the suffix "a," establish an operative connection between the rear end of the link 53^a and the toggle mechanism.

From the description thus far it will be seen that rocking of the main operating shaft 44 counterclockwise moves the links 41 and 41^a rearwardly to straighten the toggle mechanism 37-38. This causes clockwise rocking of the rocker arms 31 and 31^a so that the platen 32 and shredder bar 33 are moved upwardly to cooperate with the type 25, type bar 28 and type bar extension 29 to print the amount in a check inserted in the throat 21 and further to shred or perforate that portion of the check on which the name of the payee is inscribed. When the parts are in their initial or repose positions shown in Fig. 2 the arm 48 has carried the inking unit 49-50 into position to ink the type 25 on the printing line. When the rock shaft 44 is moved in the counterclockwise direction as aforesaid the links 57 and 57^a are drawn downwardly by rearward and downward movement of the pivot pin 40 of the toggle mechanism 37-38. This movement results in a clockwise rocking of the short arms 55 and 55^a, whereupon the long forwardly extending links 53 and 53^a are drawn rearwardly to effect a clockwise rocking of the arms 48 and 48^a, thus swinging the inking unit out of the path of the upward moving platen 32.

The rock shaft 44 projects at one side of the head 11 and has keyed or otherwise secured thereto one end of a manual operating lever 58. A return spring 60^a for the operating lever is distended between the cross rod 39 and a point of connection 60^a with a lower part of the plate 43 which is constrained for pivoting with the

main operating shaft 44. When the lever is reposed in its starting position it extends substantially directly upward from the axis of the rock shaft 44 (Fig. 2). The machine is operated by swinging the lever 58 from the Fig. 2 position to the Fig. 3 position. In this movement it will be noted that the lever travels through an arc of less than 90°. This arrangement constitutes an important feature of the invention, inasmuch as initial movement of the lever 58 is forwardly and downwardly. As stated above the characteristic constriction of prior machines was such that the initial position of the lever was inclined rearwardly at a substantial angle to the vertical, with the result that the initial movement of the lever was upwardly and then forwardly and downwardly. Force components applied to those machines pursuant to this initial upward movement of the lever decreased the force of contact of the rear feet with their supporting surface and materially contributed to the tendency of the machines to twist about a vertical axis, and this tendency was aggravated by the shortness of the base of those machines from front to back. These disadvantages are eliminated according to the present invention by the arrangement of the link 41 and toggle mechanism 37-38 and rockable member 43 in such manner that the operating lever 58 may assume the initial position shown in Fig. 2 (as an expedient for shortening this description reference is frequently made only to the functions of parts, as links 41, at the one side of the machine, but it should be understood that there is also the complementary function of the companion parts, as 41^a, at the opposite side of the machine). This result is due largely to the increased length of the body which permits the use of the longer link 41. The increased distance between the rock shaft 44 and the rear end of the body further makes it practicable to dispose the connecting pin 42 for the link 41 so this pin is substantially directly below the axis of the rock shaft 44 when the operating handle is in its position of repose, and this in turn makes it possible to rotate the operating handle less than 90° in causing the bell-crank arm 45 and the link 41 to approach their straight-line force-multiplying position of Fig. 3 concurrently with the platen and shredding bars arriving at their pressure-requiring positions.

Resetting mechanism is provided for returning all the type-carrying members 23 to zero after each printing operation, unless such mechanism is locked out in a manner to be presently set forth. This feature is provided in the machine to facilitate accurate set-up of the printing line for successive checks of different amounts, or alternatively leaving the set-up undisturbed when operating on a run of checks of equal amount. The resetting or clearing mechanism of this machine includes a resetting element in the form of a bail 59 having a transverse bight and a pair of curved legs. Each leg is carried by a proximate side wall of the head 11 on a pivot pin 60 and one of the legs has a rearward extension 61. Counterclockwise swinging of the bail 59 carries its bight against the shanks of finger-operated members of any of the printing segments which are set out of the zero position, whereby the downwardly swinging bight returns these segments to zero. Means for swinging the resetting bail 59 is operated from the rockable plate 43. The crank arm 46 of the rockable plate 43 pivotally carries the lower end of

an angularly shaped link or connecting element 63, upon a pivot pin 62. This link extends forwardly from the crank arm 46 and then upwardly and is provided in its upwardly extending portion with an arcuate slot which forms a primary track 64. The upper end of this slot is turned laterally to provide a secondary track 65. A follower pin 66 on the rearward extension 61 of the resetting bail 59 is slideable within the primary and secondary tracks 64 and 65. The link 63, being pivoted on the crank arm 46 by the pin 62, is therefore shiftable with respect to the crank arm 46 even though movable therewith, and this movement or shifting of the link 63 relative to the crank arm 46 is controlled by engagement of the follower 66 with the primary and secondary tracks 64 and 65. Link 63 is urged to pivot counterclockwise about the pin 62 by a torsion spring 67 wrapped around such pin and having its opposite ends respectively engaging the link 63 and rock shaft 44 as shown in Fig. 3. When the parts are in the positions shown in Fig. 2, the arc of the primary track 64 coincides with a circle described about the axis of the pin 60 as a center. This permits the pin 66 to be retracted from the upper end of the slot 65 to the lower end thereof when the bail 59 is moved upwardly from the clearing position shown by dot-dash lines in Fig. 2 pursuant to manual resetting of the tabs 26. The upper forward portion of the link 63 is provided with a cam profile 67^a deflectable by a stud or pin 68 anchored in the proximate side wall of the head 11 as the operating handle 58 finally approaches its repose position for pivoting such link to displace its shoulder 67^b from beneath the bail clearing pin 66 and thus placing the arcuate slot portion 64 in registry with said clearing pin to facilitate its movement to the lower end of the slot portion 64 pursuant to upward movement of the bail 59.

Mechanism for selectively locking out the type resetting means includes a manually operable cam 69 pivoted in the proximate side wall of the head 11 and operable by means of a knob 70 projecting outwardly from the body (Fig. 4). Counterclockwise rotation of the cam 69 is limited by a stop pin 71 carried by the proximate side wall of the head 11. When in this position, the cam permits the spring 67 to pivot the link 63 for placing the shoulder beneath the resetting pin 66 as shown in Fig. 3 so a clearing movement is imparted to the bail 59 when the operating handle is released and returned to its repose position of Fig. 2. When the cam 69 is pivoted clockwise from the Fig. 3 position its lobe 71^a is placed in the path of the link 63 for removing the shoulder 67^b from beneath the resetting pin 65 so the slot portion 64 will slide idly along this pin and permit the type to remain set while the operating handle is moved back to its repose position.

The basic structure of the machine is completed by a plurality of transversely stay rods 73 which extend across between opposite side walls of the body.

Guide slots 76 extending along opposite sides of the upper flat face of the base 10 slideably receive stop tabs 74 projecting upwardly from a triangular stamping 75 beneath such face. A reinforcing flange 76^a is upon the front edge of the stamping and a down-turned tab 76^b on its rear apex slides in a stabilizing slot 76^c. Fore and aft adjustment of the tabs 74 which are stops for the leading edge of an inserted instrument is

made according to the type of check or check-voucher sheet to be handled by the machine.

The rockable member 43 is provided with a pair of radially projecting stop portions 71 and 72 which are respectively engageable with a stop pin 79 when the member 43 assumes the positions shown in Figs. 2 and 3, the structure delineating the arcuate travel of the operating lever 58. The pin 79 is rigidly carried by a proximate side wall of the body of the machine.

Operation

Because of the depth of the throat 21, the machine herein disclosed is capable of handling all forms of checks or check-voucher units. In cases where a check writer is used on ordinary checks or checks with vouchers attached thereto along the short side thereof, there is no problem, since a check of either of these types need be inserted in the throat of the machine only sufficiently far to enable the printing and shredding means to operate in the proper place on such check. In this respect prior machines were fairly satisfactory. It is found, however, that various business houses make use of a check-voucher unit or sheet of the type shown in Fig. 5, wherein the voucher is attached to the check along the upper longitudinal side of the check. The legends and information on the check and voucher appear in the order shown. A check-voucher unit of this type is found to facilitate typing thereon, since the voucher portion may be filled in first and the check may be completed subsequently. In the use of this type of unit, the voucher and check remain attached until the voucher is detached by the payee of the check. Although such check-voucher sheet or unit possesses several advantages from the standpoint of efficiency and desirability in the writing thereof, it has been found impossible to protect such checks with check-protecting machines of the type heretofore known. The principal cause of this difficulty results from the inability of such prior machines to handle the check-voucher sheet, since the relatively short or shallow throat of such machines could not accommodate the voucher while the check was being printed and shredded.

According to the present invention, the throat 21 is deep or long enough to receive the check-voucher sheet when such sheet is fed into the throat voucher first. There is sufficient room in the throat so that the voucher may occupy the rearward portion of the throat while the appropriate portion of the check is disposed in position to be protected by the printing and shredding means.

The member 75 is longitudinally slidable in the guides 76 at opposite sides of the base 10. The stops 74 may be adjusted to vary the longitudinal distances thereof rearwardly of the printing and shredding mechanism so that checks or check-voucher sheets of different types and widths may be accommodated in the throat 21. For example, if it is desired to write and protect a check of the type which has no voucher attached thereto, or of the type in which the voucher is attached other than as shown in Fig. 5, the stops 74 may be moved forwardly with respect to the printing and shredding mechanism so that the distance between the stops and the printing and shredding mechanism corresponds to the distance between the upper edge of the check and those spaces on the check that receive the amount and the name of the payee.

The operation of the printing and shredding mechanism has been set forth in substantial detail above and need not be repeated. When the operating lever 58 is moved forwardly and downwardly to operate the printing and shredding mechanism, there occurs a simultaneous operation of the resetting mechanism, provided that the resetting mechanism is not locked out of operation by the cam 69. Assuming that the resetting mechanism is not locked out, the parts start in the position shown in Fig. 2, proceed in one phase of their movement to the positions shown in Fig. 3, and return in a second phase of their movement to the positions of Fig. 2. When the finger-operated control members 26 for the type-carrying members 23 are moved upwardly in the slots 15, they are always in the path of the bight portion of the resetting bail 59. When the operating lever 58 is rocked forwardly and downwardly, the crank arm 46 on the rock shaft 44 swings in a counterclockwise direction and carries with it the resetting link 63. During this downward movement of the link 63, the follower pin 66 on the extension 61 of the resetting bail 59 slides along the rearmost edge of the curved slot 64 until the shoulder 67 passes beneath such pin whereupon the spring 67 pivots the link 63 to place the shoulder beneath such pin. When the operating lever 58 reaches the limit of its downward movement (Fig. 3), the link 63 simultaneously reaches its downward limit, and the shoulder will be spaced downwardly from the follower 66. When the operating lever is allowed to return to its starting position under the force of spring 60^a, the toggle mechanism operates to release the platen from impression relation with the characters 25 in the printing line while the shoulder 67^c is moved upwardly into contact with the follower 66 preparatory to causing reset movement of the bail 59. Thus assurance is had that no reset movement is imparted to any of the type segments while the platen is pressed against their type characters. Following abutment of the shoulder 67^c with the follower 66, continued return movement of the operating handle is accompanied by additional upward movement of the shoulder 67^c to effect counterclockwise rocking of the resetting bail 59 and the return of all "set" operating members 26 to their zero positions. Of course, the bail will have no effect on members 26 that are already in their initial or zero positions. As the link 63 approaches the limit of its upward movement, the upper forward corner 67^b strikes the deflector stud 68 to withdraw the secondary track 65 and shoulder 67^c and place the primary track 64 in endwise registry with the follower 66. This disposes the track 64 for receiving the follower pursuant to upward movement of the bail bight by upwardly moved members 26 in the setup of a new printing line.

The foregoing operation of the resetting link 63 with respect to the follower 66 on the resetting bail 59 follows from the fact that the position of the bail 59 after its resetting operation is determined by the position of that type-carrying member 23 that is moved the greatest distance upwardly. In other words, the resetting bail, having been moved to the position shown in broken lines in Fig. 2, is not automatically returned to the full line position shown in Fig. 2. The mechanism in this respect is considerably simplified and departs from known constructions by the elimination of a return spring. It is found that the automatic return of the resetting

bail by spring action results in objectionable noise, and such automatic return is not really necessary, since the resetting bail may be returned to an appropriate initial position by being engaged by whichever finger-operated members 26 are moved upwardly when the type-carrying members 23 are repositioned for the writing of subsequent checks. The arrangement in the present machine is such that no additional effort is required to move the resetting bail 59 in 10 the manner aforesaid.

In the event that it is desired to write and protect a plurality of checks in the same amount, the resetting mechanism may be locked out so that the resetting bail 59 does not change the positions of the type-carrying members 23. To accomplish this result the cam 69 is rotated in a clockwise direction so that the long lobe thereon is in position to engage the lower forward corner of the link 63 as the link is moved downwardly to the position shown in Fig. 3. The long lobe on the cam 69 then deflects the link 63 rearwardly and prevents forward shifting thereof by the spring 67 and thus precludes engagement of the secondary track 65 with the follower 66 on the resetting bail 59. As long as the cam 69 is in the position thus described, the follower 66 will travel idly in the primary track 64 and the position of the resetting bail 59 will not be changed.

Embodiment of Figs. 6 and 7.

Most parts of the modification shown in Figs. 7 and 8 like those in the first embodiment and such parts are identified by the same respective reference characters. Corresponding parts are designated by the same respective reference characters plus one hundred; for example, the return spring for the operating lever 58 is designated 160^a instead of 60^a as in the first embodiment. The principal change is in omission of the frame-mounted stud 68 and substituting a pin 201 on the reset bail 159 as the means for deflecting the link 163 to carry the shoulder 167^c from under the pin 166 while the operating handle is in its repose position, Fig. 6. It will be assumed that the operating handle has been moved to the operated position of Fig. 7. Upon subsequent release of the handle it will be moved clockwise upwardly by the spring 160^a together with the member 63 toward the repose position. During this clockwise movement of the member 63 the link 163 will be projected generally endwise upwardly while the shoulder 167^c approaches the pin 166 on the extension 161 of the reset bail. Spring 67 causes the back side of the secondary track 65 to slide against the pin follower 166 at this time. Meanwhile the link 41 will be operating the toggle mechanism (as 37-38 of the first embodiment) for withdrawing the platen from impression relation with the printing line of "set" printing characters, so that by the time the shoulder 167^c reaches the pin 166 and commences reset movement of the bail 159 the printing characters will be released and resettable without likelihood of tearing the check which has been printed upon. The shoulder 167^c of the upwardly moving link will continue to press the pin 166 upwardly until the bail has reached the reset position shown by broken lines in Fig. 6, whereupon an angle portion 202 of link 163 abuts the pin 201 and deflects the shoulder 167^c from beneath the pin 166, leaving it in the dotted line position of Fig. 6. This places the upper end of the curved slot 164 in registry with the pin 166 so it can be moved downwardly thereinto pursuant to manual reset-

ting of the type segments and concomitant clockwise displacement of the bail.

General statement

The increased length of the machine, in addition to accommodating more efficient mechanism and increased mechanical advantage in the linkage for operating the rocker arms 31 and the inking roller arms 48, provides also for a more appropriate disposition of the resetting mechanism. It is to be noted that the resetting link 63 and the connection thereof to the resetting bail 59 and crank arm 46 on the rockable member 43 is positioned in the space between the transverse shaft 22 and the rock shaft 44. This is in contradistinction to known constructions in which corresponding, though dissimilar, mechanism is crowded about the axis of the shaft that carries the type-carrying members, which rather undesirable construction results from the close crowding of the printing mechanism shaft and operating lever-rock shaft.

Other desirable characteristics of the invention as embodied in the preferred form herein disclosed will occur to those skilled in the art, as will various modifications and alterations in the detailed structure illustrated and described. It is not desired, however, that the principles of the invention be delineated by the particular structure and mode of operation set forth herein.

What is claimed is:

1. A check protector, comprising: a body including an elongated fore and aft extending base with an elongated upper face extending lengthwise of said base, and a head disposed above the base in vertically spaced relation thereto, the space between the base and head providing an elongated horizontal throat generally coextensive with said upper face of the base; means connecting the base and head together at their rear ends leaving the throat open at its front and sides; printing means disposed partly in the base and partly in the head and located near the front of the throat; type-changing mechanism associated with the printing means and carried by the head near the front of the throat; an operating lever carried by the head on a transverse axis spaced rearwardly of the type-changing mechanism and substantially centrally positioned between the front and rear ends of the base; type-resetting means positioned in the head in the space between the type-changing mechanism and the operating lever axis and operatively associated with the type-changing mechanism and the operating lever; a rocker arm disposed longitudinally in the base and having its front end operably connected with the printing means and its rear end in proximity to the rear end of the elongated throat; and means operatively connecting the operating lever and rocker arm, said connecting means including force-multiplying toggle mechanism at the rear of the body and operably connected with said rocker arm, and a force-multiplying linkage operably connected between said toggle mechanism and the operating lever.

2. A check protector, comprising: a body including an elongated fore and aft extending base with an elongated upper face extending lengthwise of the base, and a head disposed above the base in vertically spaced relation thereto, the space between the base and head providing an elongated horizontal throat generally coextensive with said upper face of the base; means connecting the base and head together at their rear

ends leaving the throat open at its front and sides; printing means including a platen mounted on the base and changeable type mounted on the head near the front of the throat; type-changing mechanism associated with the printing means and carried by the head near the front of the throat; an operating lever for the printing means carried by the head on a transverse axis spaced rearwardly of the changeable type and substantially centrally positioned between the front and rear ends of the body; type-resetting means positioned in the head in the space between the type-changing mechanism and the operating lever axis and operatively associated with the type-changing mechanism and the operating lever; a rocker arm disposed longitudinally in the base and having its front end serving as the mount for the platen and its rear end in proximity to the rear end of the elongated throat; force multiplying toggle mechanism at the rear end of the body and operably connected to the rear end of the rocker arm; and force multiplying toggle operating means including a link pivotally connected between the operating lever and the toggle mechanism, the pivoted connection between the link and operating lever being substantially directly below the axis of the operating lever and being swingable into a position substantially on a line extending between the axis of the operating lever and the pivoted connection of the link with the toggle mechanism incident to unbuckling the toggle mechanism.

3. A check protector, comprising: a body having an elongated fore and aft extending base with a flat upper face, and a head spaced above the base and secured to the base at only the rear end thereof, the space between the head and base providing an elongated throat open at its front and sides; printing means carried by the body near the front of the throat; and means for operating the printing means, including a rock shaft carried by the body for rocking about an axis transversely of the base and positioned to the rear of the printing means and substantially centrally between the front and rear ends of the body, a rocker arm disposed longitudinally in the base and operably connected with said printing means, toggle means at the rear of the body and unbuckleable to operate said rocker arm, a crank connected to the rock shaft and depending substantially directly below the axis thereof, a link operably connected between the crank and the toggle mechanism, and an operating lever fast on the shaft and extending in a reposing position substantially directly vertically upwardly from the shaft when the toggle mechanism is buckled, the crank, link and toggle mechanism being so constructed and arranged as to swing the connection between the crank and link into a position substantially onto a line extending between the rock shaft axis and the connection of the link with the toggle mechanism pursuant to only approximately 90° swinging movement of the lever to effect unbuckling of the toggle mechanism and consequent actuation of the printing means.

4. In a check protector having a body, printing mechanism including type-carrying members individually settable about a common axis transversely of the body, and means for operating the printing mechanism including a rockable operating member oscillatable between a position of repose and an operated position, the combination with the type-carrying members of: a type-resetting bail having a bight and a pair of legs positioned in the body with the legs pivoted on a transverse axis and with the bight arranged to engage the type-carrying members, whereby the bight may sweep through an arc about the pivot axis of the legs to reset the type-carrying members to their initial positions; means providing a crank arm swingable by the aforesaid operating member; a pin on one leg of the bail and sweepable through an arcuate path attendant to movement of the bight through its arc; a link pivoted to the crank arm and having means engaging the pin including a long arcuate primary track and an angularly related relatively shorter secondary track, means for holding said link to dispose the arcuate track thereof coincident with the arcuate path of said pin while the rockable operating member is in its position of repose whereby the bail can retractively sweep without moving the link, said arcuate track accommodating movement of the link relatively to the pin pursuant to an initial phase of movement of the operating member from the repose position toward the operated position; and means for shifting the link about its pivot on the crank arm for switching the pin to the secondary track during a succeeding phase of such operating member movement whereby reverse movement of the link by the crank arm will effect type-resetting movement of the bail.

5. The invention set forth in claim 4, in which: adjustable means is provided for engaging the link to prevent shifting of the link with respect to the crank arm and thereby precluding switching of the pin to the secondary track.

6. The invention set forth in claim 4, in which: said means for holding the link in the position placing the arcuate track coincident with the arcuate path of the pin is operable to engage the link after predetermined reverse movement thereof with the pin in the second track for re-shifting the link to reestablish coincidence of said arcuate track with the path of said pin.

LLOYD H. FENSTERMAKER.
